UNITED STATES PATENT OFFICE

120,235

DESIGN FOR A PRESS FRAME

Stewart Bolling, Cleveland, Ohio

Application February 5, 1940, Serial No. 90,049

Term of patent 7 years

To all whom it may concern:

Be it known that I, Stewart Bolling, a citizen of the United States, residing at Cleveland, in the county of Cuyahoga and State of Ohio, have invented a new, original, and ornamental Design for a Press Frame, of which the following is a specification, reference being had to the accompanying drawing, forming part thereof.

Figure 1 is a front elevational view of a press frame showing my new design.

Figure 2 is a side elevation.

Figure 3 is a top plan view.

I claim:

The ornamental design for a press frame, as shown.

STEWART BOLLING.
